(57) CLAIM

The ornamental design for a bottle, as shown and described.

DESCRIPTION

FIG. 1 is a perspective view of a bottle showing my new design;

FIG. 2 is a left side view thereof, the right side view being a mirror image;

FIG. 3 is a front view thereof, the rear being a mirror image.

FIG. 4 is a top elevational view thereof; and,

FIG. 5 is a bottom plan view thereof.

The broken line showing of environment is for illustrative purposes only and forms no part of the claimed design.
